UNITED STATES PATENT OFFICE.

JOHN HART WILSON, OF BURKBURNETT, TEXAS.

SELF-PROPELLED WINCH.

Application filed February 29, 1924. Serial No. 696,037.

To all whom it may concern:

Be it known that J. JOHN HART WILSON, a citizen of the United States, and residing at Burkburnett, county of Wichita, State of Texas, have invented certain new and useful Improvements in Self-Propelled Winches, of which the following is a specification.

The present invention relates to winches, particularly to self-propelled winches used in oil field operations in raising from and lowering into oil wells, tools, tubing, rods and other implements.

The objects of the invention, generally stated, are to provide a winch which combines great power with speed of maneuvering, ease of manipulation, lightness of construction for a given strength, safety for its operator, and moderate cost. It is a particular object of the invention to provide a winch construction which can be applied conveniently to the well-known Fordson tractor whereby the advantages enumerated above are realized, and at the same time an increased economy of operation obtained.

25 The invention is not limited, however, to an attachment for a tractor of any particular kind or make and may be incorporated in a belt tread as well as in a wheeled tractor.

It will be understood that that form which is illustrated in the accompanying drawings and herein described is given by way of example only, and that the design and arrangement of the component elements may be greatly modified without departing from its 35 spirit and scope.

In the drawings:

Figure 1 is a side elevation of the improved winch, one front and one rear wheel being removed however, so that the framework and moving parts may be more clearly observed;

Figure 2 is a top plan view of the same, part being broken away;

Figure 3 is a front elevation of the improved winch;

Figure 4 is a section on line 4-4 of Figure 1;

Figure 5 is a section on line 5-5 of Figure 4;

50 Figure 6 is a section on line 6-6 of Figure 1;

Figure 7 is a section on line 7-7 of Figure 3;

Figure 8 is an enlarged section on line 8-8 of Figure 7;

Figure 9 is an enlarged section on line 9-9 of Figure 7;

Figure 10 is an enlarged section on line 10-10 of Figure 7;

Figure 11 is a front elevation of the left hand end casting shown in Figure 7 as viewed from the left of Figure 7;

Figure 12 is an enlarged view, in section, of certain of the brake operating mechanism shown in elevation in Figure 6;

Figure 13 is a top plan view, partly broken away, of the clutch operating mechanism;

Figure 14 is a section on line 14-14 of Figure 13;

Figure 15 is a section on line 15-15 of Figure 13;

Figure 16 is a side elevation of the rear axle housing; and

Figure 17 is a section on line 17-17 of Figure 1, to an enlarged scale.

The tractor illustrated in the drawings is the well-known Fordson tractor, and the advantages of adapting this tractor for the purposes intended, from the standpoint of economy and simplicity of construction, will be apparent to those skilled in the art. As before pointed out, however, the invention is limited to no particular form of tractor, and, while in the embodiment herein disclosed it is particularly adapted to a wheeled tractor, many of its features may be incorporated if desired in a tractor of the belt tread type.

The crank case of the tractor is indicated at 10, its engine block at 11, fuel oil tank at 12, radiator at 13, rear axle housing at 14, rear wheels at 15 and front wheels at 16. The driver's seat is indicated at 18' and the steering wheel at 18. A number of the other features of the tractor have been omitted from the drawings for the sake of clearness. The winch drum is indicated at D, and the axle upon which this drum is non-rotatably secured is indicated at 17. This axle extends transversely of the tractor, and its ends are supported in babbitt lined bearings 18, which are mounted upon horizontally extending side frame members 19. These side frame members are, in the particular embodiment illustrated, formed of channel irons with their flat faces outward,

2
and the bearings 18 are secured by suitable bolts to these channel irons, certain of the bolts passing through the top flanges of the channels, and certain other bolts passing through the webs of the channels.

The side frame members 19 project for a considerable distance in advance of the tractor, and the forward portions of these members are horizontally disposed, while the rearward portions are downwardly and rearwardly inclined, as shown clearly in Figure 1. The rear and lower ends of the side frames are provided with inwardly offset portions or feet 20 which rest on paired seats on the rear axle housing, and these feet 20 are securely retained in this position by U-shaped double ended bolts 21 provided with nuts 22. At their mid points, the side frame members are supported by inclined upright braces 23, the lower ends of which are bolted to the crank case flange by bolts 24, and the upper ends to the webs of the side frame members by bolts 25.

Laterally extending tying-in members 26 secure the top flanges on the side frame members to the head of the cylinder block to prevent lateral spreading of these members. In addition, the side frame members are connected by a transversely extending channel member 27 in advance of the radiator 13. A V-shaped brace 28, clearly shown in Figure 6, has its upper ends secured to the bottom flange of the cross channel 27 and extends downwardly and rearwardly and has its lower end rigidly supported in a manner hereinafter to be more fully described. This brace 28, supplemented by a vertically extending brace, comprising angle irons 29 having their upper ends secured to cross channel 27, and their lower ends supported from the axle 30 in a manner hereinafter to be more fully described, supports the forwardly extending portions of the side frame members 19 and transmits the weight of the drum and its associated mechanism to the frame and wheels. It will thus be seen that a simple and light frame mechanism is provided for supporting the winding drum, yet which frame is braced securely against all possible strains which may be imposed upon it. This frame, in addition to supporting the winding drum, supports the brake mechanism, the counter shaft and other members of the control mechanism, as will be hereinafter more fully brought out.

Referring now more particularly to the winding drum itself, it will be seen that this drum comprises a cylindrical barrel portion 31, the ends of which are secured upon the hubs 32 of the circular end flanges 33. Long bolts 34 extend parallel to the drum shaft 17 and tie the end flanges 33 together. Set screws 35 are provided which extend through suitable apertures in the

hubs of the end flanges and into the shaft 17 so that the drum and shaft are constrained to rotate together. Each of the end flanges 33 is provided with a short cylindrical outwardly extending portion 36 to circumferentially grooved to provide a seating surface for the brake bands 37 and 38, respectively, the former of which constitutes the emergency brake and the latter the foot brake. To the right hand flange 33 shown in Fig. 4 (that is, to the left hand side of the drum looking forwardly along the tractor) is secured a drive sprocket 39 by means of bolts 40. Each of the end flanges is provided with exterior radially arranged integral ribs 41, which in reality constitute fan blades which cause a turbulence and flow of air as the drum rapidly revolves, whereby a decided cooling effect is realized which prevents overheating of the braking surfaces even under the hardest usage to which the winch may be subjected. The brake bands and braking surfaces also are designed to have a very large area of contact to provide a maximum safety in the operation of the winch, as well as a minimum wear and heating.

The lower end of each brake band is connected by suitable rivets to a rod 45 disposed tangentially to the braking surface and having its outer end threaded and extending through a suitable aperture in a bracket 46, riveted to the cross channel member 27. Suitable nuts 47 on opposite sides of brackets 46 permit rods 45 to be longitudinally adjusted so that the tightness of the brake bands may be quickly regulated. The upper ends of the brake bands are looped and extend around pins 48 which extend through apertures in the spaced arms of the short brake levers 49 and 50 respectively (see Figure 6). Brake lever 49 is keyed or pinned upon the brake shaft 51 which extends transversely of the machine and has its ends rotatably mounted in bearings 52 bolted to the top flanges of the side frame members. Brake lever 50 is rotatably mounted upon shaft 51 and is provided with a cylindrical extension 53 to which the hub of an upwardly extending lever 54 is keyed or otherwise secured against rotation.

A collar 55 secured to shaft 51 by set screw 56 serves as a retaining collar to prevent longitudinal movement of the brake lever 50 on shaft 51, the opposite end of the brake lever, that is, the annular end of the sleeve portion 53 bearing lightly against the bearings 52 and being thereby prevented from sliding movement in the opposite direction. Shaft 51 extends through the left hand bearings 52 (of the machine) and has upon its outer end a second vertically extending lever 57, the levers 54 and 57 constituting the brake operating levers, it being

apparent that a rearward rocking motion of lever 54 will cause tightening of the left hand brake band, and a rearward rocking motion of lever 57 will cause tightening of the right hand brake band. To the upper end of lever 54 is pivotally secured the forward end of a link 58, the rear end of which is pivotally connected to the emergency lever 59 which in turn is pivoted at its lower end upon a short shaft 60. This shaft has one end supported in a bracket member secured to the side frame member and its other end is free. Suitable and well-known locking and releasing devices are employed so that the emergency lever 59 may be held in any desired position.

To the upper end of the foot brake 57 is pivoted the forward end of a link 62 and the rear end of this link is in turn pivoted to the upper end of a rocker 63 rotatably mounted upon a shaft 64 supported in bearings 65 secured to the side frame members. Rigidly connected by means of a short shaft with lever arm 63, but at a slight angle thereto, is a second lever arm 66, and to the upper end of this arm is pivotally connected a link 67, the lower end of which is in turn pivotally connected to the downwardly extending flange 68 of a foot pedal 69, which is mounted to rock on a short shaft 70, the outer end of this shaft being secured in a bracket 71 fastened to the side frame member, and the inner end of which is secured in a socket 72 bolted to the flange of the rear axle housing. A spring 73 having one end connected to the shaft bearing 18 and the other end connected to lever 57, tends to draw the lever forwardly and the foot brake upwardly from its limiting stop (not illustrated). Depression of the foot brake pedal causes tensioning of the spring 73 on application of the foot brake, but upon release of the pedal by the operator, the spring 73 will act to draw lever 57 forwardly and hence to cause release of the foot brake.

Extending transversely through the tractor in rear of the radiator is a counter shaft 80 having its ends rotatably mounted in bearings 81 bolted to the side frame members. Free to rotate on this shaft is a sleeve 82 having a sprocket 83 connected by chain 84 with the sprocket on the end of the winding drum, the inner face of this annular sleeve constituting a clutch face. A second sleeve 85 is splined to shaft 80, and the outer face of this second sleeve constitutes a clutch face adapted to cooperate with the face of sleeve 82. Sleeve 85 is splined to shaft 80 and rotates therewith at all times. It is movable longitudinally of the shaft however by means of a bell crank lever 86 pivoted at 87 to a bracket 88 secured to the left hand cross brace 26, the forward end of this bell crank lever being bifurcated and

provided with apertures to receive trunnions 89 integral with a collar 90 which fits within a groove 91 in sleeve 85. Movement of sleeve 85 into clutching engagement with sleeve 82 therefore causes operative connection of shaft 80 and the drum through the chain 84, and the rotation of shaft 80 may be therefore communicated to the drum at the will of the operator, who can freely move the bell crank lever 86 by means of a clutch shift lever 95 also pivoted on shaft 60 and connected to the bell crank lever by means of a link 96.

Upon shaft 80 at the right hand side of the engine is keyed or otherwise suitably secured a sprocket 97 which is connected by means of a chain 98 with a small sprocket 99 on the power take-off shaft 100 of the tractor. Power is therefore communicated through the two chains 98 and 84, counter shaft 80, and clutch mechanism to the drum, and because of the construction of the clutch mechanism, the operator may quickly and conveniently connect the power shaft 100 to the drum at any time. For certain purposes it may be desirable to take power directly from shaft 80, and for this reason this shaft is extended through its bearing 81 at its right hand end.

As shown in Figures 2 and 13, the inter-engaging faces of clutch members 82 and 85, that is, the faces 82' and 85' which mutually engage and transmit the driving force to the drum, are flat and meet in a plane which includes, or is substantially parallel to, the axis of the shaft. Furthermore, the ends of the teeth of the one member and the bottoms of the corresponding recesses of the other member are flat and disposed in planes transverse to the axis of the shaft, the teeth and recesses also being stepped as shown.

The recesses into which the clutch teeth enter when the clutch members are engaged are stepped as shown in the drawings, so that the entering angle may be small and yet the teeth prevented from rebounding excessively. Thus the rebound of each tooth will be limited by the step in its rear to a very short movement. Furthermore this formation of clutch teeth enables the clutch elements to maintain operative engagement whenever the direction of rotation of the counter shaft. The use of this type of clutch in the connection between the power shaft and drum is an important feature of the invention. The operative connection may be easily made or broken, the parts will not automatically separate, and the clutch operates with great satisfaction in the combination in which it is placed. The action of the clutch is positive and the drum is operatively connected to the power shaft whenever the clutch is thrown in, whether the drum be loaded or unloaded. With clutches

of ordinary type, satisfactory clutching action could not be had under the varying working conditions, but I have found the clutch above described to be very satisfactory.

As previously mentioned, the lower ends of the V-shaped brace 28 and the vertical braces 29, which together bear the weight of the forward end of the drum supporting the frame, have a special mounting upon the tractor frame. Thus, the lower end or apex of the V-shaped brace 28 is provided with an aperture through which a pin 101 extends, this pin projecting through aligned apertures in flanges 102 which normally project downwardly in front and rear of the front axle of a Fordson tractor. Pin 101 is normally utilized to pivotally retain this front axle.

In adapting the Fordson tractor for the present use, however, I remove the front axle and move it forwardly as shown in the drawings and place between the flanges 102 a special casting which is illustrated clearly in Figures 7 and 8. The upper portion of this casting member is provided with a central aperture 103 to receive the pin 101, and is also provided with transverse grooves or trackways 104 upon which the lower surfaces of wedges 105 slidably rest. These wedges are axially apertured to receive a bolt 106 provided with a nut 107 by means of which they may be drawn toward each other. Upon the upper inclined surfaces of the wedges, the bottom of the Fordson radiator base rests. The special casting (which I designated as C') is further provided with coplanar surfaces 108 which rest upon the top flanges of parallel and horizontally arranged channel members 109. These channel members, the flanges of which extend inwardly, retain between them the lower portion of casting C' which is provided with a transverse web 110 extending from one channel to the other, and with longitudinal flanges 111 fitting closely the inner surfaces of the channels. These flanges 111 are provided with pairs of aligned notches on opposite sides of the central transverse web 110, and through these notches extend bolts 112 which secure the casting rigidly in position, the bolt shanks fitting closely in transverse grooves in the web of the casting and positively preventing any movement longitudinally of the channel members. The downward thrust of the V-shaped brace 28, and the weight of the forward end of the tractor crank casing is therefore transmitted through casting C' to the parallel channel members 109.

These channel members 109 extend horizontally and are secured at their rear ends to the bottom of the crank case of the tractor by means of a special casting and bolts now to be described, and at their forward

ends to the front axle of the machine likewise, by special connecting means.

Projecting downwardly from the bottom of the crank case of the tractor are two parallel flanges 113 between which, in the normal construction of the Fordson tractor, the rear ends of the radius rods are pivotally secured. To secure this radius rod, a pin 114 is normally employed which extends through aligned apertures in flanges 113. In adapting the Fordson tractor for my present purposes, I move the radius rod forwardly and insert between the flanges 113 a special casting C² clearly shown in Figures 7 and 10. This casting is provided with side flanges 115 which lie parallel to the webs of the channel members and are notched at their opposite ends to receive transversely extending bolts 116 which serve to secure the channel members together and as retaining means preventing longitudinal movement of the casting. The transverse web 117 of the casting lies between the flanges 113 and is provided with an aperture 118 which receives the pin 114, shown in dotted lines. An absolutely rigid, and likewise a very strong connection, is therefore made between the bottom of the tractor crank case and the channel members 109, and without at the same time requiring the modification in any manner of the original flanges 113. Indeed the original pin 114 is used in the new construction.

The forward end of the channel members 109 is connected to the front axle of the tractor by a special casting C³ clearly shown in Figures 7 and 11. The forward portion of this casting is provided with a slot 120 to receive the axle, and the rearward and lower portion of the casting is provided with side portions 121 which fit quite closely against the inner surfaces of the side channels 109. In reality the casting comprises essentially two parallel longitudinally extending webs 122 which are provided with suitable strengthening and tying cross flanges. The webs 122 are provided with apertures to receive bolts 123 by means of which the casting is secured between the channel members against danger of displacement. A pin 124 extends through axially aligned apertures in the casting and front axle and constitutes a means for securing the axle, while at the same time permitting it to have a tilting or rocking movement in a transverse vertical plane.

A fourth casting C⁴ is also rigidly secured between the channel members 109 which casting is provided for the purpose of supporting the rear end of the radius rod. In Figures 7 and 9, this casting is clearly illustrated, and it will be seen that it comprises essentially two transverse web portions 125 in spaced parallel relationship which are connected by longitudinal webs. The trans-

verse webs are notched at 126 to receive bolts 127 which serve to tie the channel members together and to prevent longitudinal movement of the casting. The spaced upper 5 ends of the transverse webs are provided with axially aligned apertures to receive a pin 128 which also extends through an aperture in the radius rod 129. This radius rod is of ordinary construction and extends for 10 wardly toward the front axle, having its forward extremities rigidly secured to the axle.

The winch is particularly adapted for use in oil field operations and especially for lowering and raising rods, tubes and implements of all kinds into and out of oil wells, and in performing these functions, the rope or cable wound on the drum is carried upwardly to a pulley at or toward the top of 15 an oil derrick and thence vertically downwardly into the well. The pull of the cable, indicated at R in Figure 1 is thus in a nearly vertical direction. To prevent the forward end of the winch from being lifted from the 20 ground when a relatively heavy weight is being raised or lowered, it is necessary to anchor the same to the derrick sill or other heavy object. For this purpose, hooks 130 are provided, which hooks are securely bolted 25 to the side frame members slightly in advance of the drum shaft, and chains 131 are passed over these hooks and beneath the sill 132 or other object. The pull of the cable is transmitted directly by these chains to the 30 sill, and it will be seen that the hooks are so positioned that the upward pull of the cable is transmitted to the sill along lines substantially parallel to the cable, at least along lines in a plane which includes the 35 cable or very nearly includes the cable. In practice the chains are inclined downwardly and outwardly as shown in Figure 3, and the hooks are offset slightly inwardly. As a result of this arrangement, the pull of the 40 chains is exerted along lines which, if extended, will pass through the centers of the bearings 18 of the drum shaft 17. It is therefore apparent that notwithstanding the 45 great magnitude of the strain transmitted to the frame by the chains, there is no tendency of the side frame members to warp in a transverse vertical plane which would result in tilting of the bearings 18 and binding of the shaft 17. The greatest forces may 50 indeed be conveyed to the frame by the chains, and the bearings will at all times remain in true alignment permitting the shaft to enjoy free rotation and with a minimum of friction.

55 In certain instances, it is desired that the rapidity of the winding of the cable be varied. This may be accomplished by the addition of chain speed mechanism, which is contemplated by this invention, or by 60 the use of a "step-up" drum, such as shown

in section in Figure 4. This "step-up" drum comprises a short cylindrical barrel portion 140 having a disk-like flange 141 which flange and barrel portion are secured to the left hand flange 33 of the main drum 70 by means of bolts 142, the heads of which are counter-sunk to prevent interference with the cable. This flange 141 is notched at 143 so that the cable may be passed from the main drum 31 through the notch and 75 on to the "step-up" drum 140. The diameter of the "step-up" drum being much greater than the diameter of the main drum, the cable may be much more readily wound thereon or unwound therefrom. The "step-up" drum is made in two equal sections as shown clearly in Figure 5, and these sections are secured together by straps 145 so that it may be removed quickly and easily from the main drum if this is desired. 80

The tractor may be driven rapidly from one oil well or scene of operation to another and is positioned for operation quickly by merely moving it up to the sill of the oil derrick as shown in Figure 1. 90 The chains are quickly secured, the cable passed from an elevated block or pulley and the operator may then take his seat upon the usual driver's seat. The three controls of the winch mechanism proper 95 may be easily operated, and there is little chance for the operator to become confused. By engaging the clutch, the cable may be wound on the drum, and, when the clutch is released, the drum will automatically unwind due to the weight on the end 100 of the cable. The speed of lowering of the tube or rod will depend upon the retarding action which the operator exerts on the drum by means of the brake. By means of the emergency brake, the drum may be locked at any time. The use of the chain and sprocket connection between the power take-off shaft and the drum gives a flexibility and a smoothness and ease of operation not heretofore realized in self-propelled winches. The frame is light, of simple construction and relatively inexpensive to fabricate and assemble, yet at the same time providing a drum supporting structure 110 of great strength. 115

As previously pointed out, the principles of the invention may be carried out in different ways, and the self-propelled winch above described and illustrated in the accompanying drawings, is given by way of example only. The design and arrangement of the component elements of the invention may be varied and modified considerably without departing from the spirit and scope 120 of the invention.

Having thus described my invention what I claim as new and desire to secure by Letters Patent is:

1. A coupling block for attaching two 130

horizontally disposed longitudinally extending members to the bottom of a vehicle comprising a transverse web portion and two parallel flanges springing from each face thereof, the web portion being adapted to be secured in a vertical position to the vehicle bottom, and the flanges to the two longitudinal members.

2. A coupling block for attaching two horizontally disposed longitudinally extending members to the bottom of a vehicle comprising a transverse web portion adapted to extend between two parallel flanges projecting downwardly from the vehicle bottom, said web having an aperture therethrough for the passage of a coupling pin, and said web having two parallel flanges springing from each face thereof, the web portion being adapted to be secured in a vertical position to the vehicle by means of said pin, and the flanges to the two longitudinal members.

3. A coupling block for attaching two horizontally disposed longitudinally extending members to the bottom of a vehicle comprising a transverse web portion and two parallel flanges springing from each face thereof, the web portion being adapted to be secured in a vertical position to the vehicle bottom, and the flanges to the two longitudinal members, said flanges being provided with recesses for the reception of bolts passing from one longitudinal member to the other.

35. 4. A coupling block for attaching two horizontally disposed longitudinally extending channel members to the bottom of a vehicle comprising a transverse web portion and longitudinally extending channel engaging portions having surfaces adapted to closely fit the inner surfaces of the channels, the web portion being attachable to the vehicle.

45. 5. The combination with a vehicle having two transversely arranged spaced parallel flanges projecting downwardly therefrom, of two longitudinally extending horizontal beam members, one on each side of said flanges, and means for coupling the beam members and flanges, which means comprises a coupling block having a web portion adapted to extend between and to be secured to said flanges, and parallel flanges springing from said web and adapted to be secured to said beam members.

60. 6. The combination with a vehicle having two transversely arranged spaced parallel flanges projecting downwardly therefrom, of two longitudinally extending horizontal channel members arranged with webs vertical and flanges extending toward each other, one channel being on each side of said flanges, and means for coupling the channel members to the flanges, which means com-

prises a coupling block having a web portion 65 adapted to extend between and to be secured to said flanges and parallel flanges springing from said web and lying within the grooves of the channel members.

7. The combination with a vehicle having 70 two transversely arranged spaced parallel flanges projecting downwardly therefrom, of two longitudinally extending horizontal channel members arranged with webs vertical and flanges extending toward each other, 75 one channel being on each side of said flanges, and means for coupling the channel members to the flanges, which means comprises a coupling block having a web portion adapted to extend between and to be secured to said 80 flanges and parallel flanges springing from said web and lying within the grooves of the channel members, said flanges having bolt receiving recesses and bolts extending through said channel members and flanges 85 and holding said channels in contact with the coupling.

8. In a vehicle underframe construction, in combination, two parallel channel members arranged with webs vertical and respective 90 flanges extending toward each other in the same plane, of means for attaching other members to said channel members above the same, said means including a coupling block between said channel members and having 95 surfaces fitting the inner walls of said members, and an aperture through which a coupling pin may be passed.

9. In a vehicle underframe construction, in combination, two parallel channel members arranged with webs vertical and respective flanges extending toward each other in the same plane, of means for attaching other members to said channel members above the same, said means including a coupling block between said channel members and having surfaces fitting the inner walls of 100 said members, and an aperture through which a coupling pin may be passed, and transverse bolts passing through the channel members and to clamp the block between said members.

10. In a vehicle underframe construction, in combination, two parallel channel members arranged with webs vertical and respective flanges extending toward each other in the same plane, of means for attaching other members to said channel members above the same, said means including a coupling block between said channel members and having surfaces fitting the inner walls of 115 said members, and an aperture midway between the channel members but adjacent the upper edge of said block for the passage of a coupling pin.

In testimony whereof I hereunto affix my signature.

JOHN HART WILSON.
